Primary Examiner — Elizabeth J Oswecki*Assistant Examiner* — Yelizaveta Y Masalimova(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines depicting the remainder of the shoe show features that form no part of the claimed design.

1 Claim, 3 Drawing Sheets(56)
